UNITED STATES PATENT OFFICE.

ELI B. GOLDSTEIN, OF CHICAGO, ILLINOIS.

DESIGN FOR AN INKWELL.

59,004.

Specification for Design.

Patented Sept. 13, 1921.

Application filed February 26, 1921. Serial No. 448,249. Term of patent 14 years.

To all whom it may concern:

Be it known that I, ELI B. GOLDSTEIN, a citizen of the United States, residing at Chicago, in the county of Cook and State of Illinois, have invented a new, original, and ornamental Design for an Inkwell, of which the following is a specification, reference being had to the accompanying drawings, forming part thereof.

Figure 1 is a perspective view of an inkwell of my new design, and

Fig. 2 is a vertical sectional view through the same.

I claim:

The ornamental design for an inkwell, as shown.

In testimony whereof I have hereunto signed my name in the presence of two subscribing witnesses.

ELI B. GOLDSTEIN.

Witnesses:

ROY W. HILL,
BERTHA HARTMANN.
